UNITED STATES PATENT OFFICE.

ORVILLE D. BARTOW, OF PHILADELPHIA, PENNSYLVANIA.

PORTABLE CONCRETE-MOLD.

1,190,977.

Specification of Letters Patent.

Patented July 11, 1916.

Application filed August 26, 1915. Serial No. 47,625.

To all whom it may concern:

Be it known that I, ORVILLE D. BARTOW, a citizen of the United States, residing at Philadelphia, in the county of Philadelphia 5 and State of Pennsylvania, have invented new and useful Improvements in Portable Concrete-Molds, of which the following is a specification.

The invention relates to molds and more particularly to molds for concrete construction and the like, and has for an object to provide a mold for building walls and abutments or the like of concrete or some other cementitious materials.

Among other features the invention comprehends a mold, preferably formed in parts, so arranged and associated that one will depend upon the other to insure a rapid and efficient wall structure. To this end the parts or mold sections can be readily assembled and as easily and quickly separated, thus not only affording a convenient means for finishing the face or faces of the structure but also permitting of the finishing operation on one part of the structure while the other part is still in course of erection.

Still further objects and uses of the invention reside in a mold, which provides a support for a scaffold, adapted to the convenience and safety of the persons who pour or otherwise place the cement in the mold.

A still further object of the invention is the provision of a mold of this character which is extremely simple in construction, portable, strong, durable, reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing the figure represents a fragmentary perspective view showing the wall in the course of construction with the mold constructed in accordance with the invention applied.

Referring to the drawing in detail, A designates a base or foundation slab, preferably made from concrete, cement, or the like, and from which rises the wall B, preferably made from concrete, cement or the like. At the inner side of the face of the wall are arranged spaced parallel vertical

studs 5, to which are secured sheathing strips 6, on the inner face of which are secured spaced vertical strips 7 forming air spaces. Connected to these strips 7 is the lathing 8 carrying the plaster 9 in the ordinary well-known manner. To each vertical stud 5 are secured the floor joists 10, the sheathing 6 being designed to serve as one wall for the mold hereinafter fully described.

The mold comprises a plurality of sections C, only two of the same being shown in the drawing, and each includes a plurality of interfitted tongue and groove boards 11 secured to brace rails 12 which are formed with correspondingly beveled ends 13 so that on the stacking of the sections C the rails 12 will overlap each other at their beveled ends on the respective sections to closely and strongly fit the same together.

Mounted in each section C of the lowermost board 11 and at opposite sides of the intermediate rails 12 and on the inner side of each outermost rail are holding pins 14, about which are adapted to be twisted the ends of anchoring wires 15 which are trained about the alternate studs 5. These wires 15 however are initially twisted around the rails 12 and are only untwisted from the rails and twisted around the pins 14 when it is desired to remove a lower section without disturbing the position of the next superposed section. Thus when several of the sections C are fitted with relation to each other, as shown in the view in the drawing, the wires 15 are first trained about the rails 12 and have their ends twisted together to firmly secure the said sections in place, while later when a section is removed the wires are fastened to the pins 14 for holding a section in position and preventing the dropping or lowering thereof, and which would ordinarily occur when a section is removed if the wires were not arranged as mentioned.

Adapted to be anchored in the ground spaced from the wall of the building during the course of erection thereof is a scaffold 16, to each vertical member of which is fixed a cross stud 17 having at one end a depending block 18 for engagement with a longitudinal bar 19 fixed to the rails 12 of each section C, so that the mold, formed of the sections and component parts will in fact act as a support or frame for the scaffold structure, the

latter being provided to assist the workmen in placing the concrete.

Mounted in the studs 5 and projecting from opposite sides thereof are spikes or pins 20 which are adapted to become embedded in the cement, concrete, or the like, to hold the same in position when it becomes hardened.

Fixed to the boards 11 and projected from the faces next to the cement, concrete, or the like, from which the wall is made, are a plurality of marking strips 21 which are adapted to form grooves in the outer face of the concrete, cement, or the like to give the appearance thereto, as being made from tiles or blocks, these strips to extend vertically horizontally or in any desired direction.

It will be particularly noted that the wires 15 occur in the lines of the marking strips and that the former are adapted to be cut off inside of the face of the wall, the marking strips and resulting grooves being also provided to hide the joints which would plainly show in instances where the concrete is poured at different times. To this end the grooves can be suitably filled with a finish or other mixture of concrete, and the facings of the mold painted or otherwise marked to show where the joints will occur.

What is claimed is:—

1. In a concrete mold, the combination with spaced vertically disposed studs, of a plurality of false-work forms, each including interfitted tongued and grooved boards 35 and transverse beams secured to said boards, said beams being correspondingly beveled at opposite ends, whereby, on stacking the forms one above the other, adjacent ends of the beams will overlap each other, tie wires 40 embracing certain of the studs and also embracing the overlapped beveled end of the beam to hold the forms in spaced relation to the studs for the molding of concrete, and pins mounted in the forms near the lower 45 edges thereof and adapted to be engaged by certain tie wires to hold the forms against lowering movement.

2. In a concrete form, the combination with vertical studs arranged in spaced relation to each other, of a plurality of removable false work forms, each including interlocked sections and transverse beams secured to said sections, said beams being inwardly beveled for the overlapping of the ends adjacent each other of the beams on the respective forms when superposed relative to one another, and tie wires embracing the studs and the said beams to anchor the forms.

In testimony whereof I affix my signature.

ORVILLE D. BARTOW.
